UNITED STATES PATENT OFFICE.

GORDON DON HARRIS, OF BAYONNE, NEW JERSEY

TUNNEL-DRiER.

1,282,822.

Specification of Letters Patent. Patented Oct. 29, 1918.

Application filed November 10, 1915. Serial No. 60,843.

To all whom it may concern:

Be it known that I, GORDON DON HARRIS, a citizen of the United States, residing at Bayonne, county of Hudson, and State of New Jersey, have invented a certain new and useful Tunnel-Dríer, of which the following is a specification.

This invention is an apparatus whereby moisture-containing materials in large quantities or in bulk may be dried rapidly and economically.

It is well established that the frequent or repeated contacts of a drying medium, such as heat, with a moisture-containing material or substance results in a more or less gradual, but none the less perceptible, reduction in the temperature of such drying medium. This condition is observable in ordinary drying machines, wherein the heat enters at a temperature say of 212° Fahrenheit and is delivered at a temperature say of 112° Fahrenheit, said condition of the drying medium being due to the heat imparted to the material during the evaporating operation.

It is apparent that under ordinary conditions the circulation of a drying medium into repeated contacts with the substance or material may be carried on to such an extent that the drying medium becomes saturated, more or less, with moisture evaporated from the material under treatment; but as such medium attains a certain degree of saturation, its temperature is reduced, hence the efficiency of the circulating medium as a means for carrying moisture is impaired both by the reduction of temperature and by the degree of saturation which it attains.

Heat is the agent by which drying or evaporating is accomplished: statistics showing that the loss of heat per cubic foot required to evaporate one grain of moisture is equal to 8½° Fahrenheit. It is also established that the presence of atmospheric air, of itself, retards the drying operation, but air is employed, mainly, as a carrier for bringing the heat units into contact, either directly or indirectly, with the material to be evaporated, and also as a carrier to remove the moisture which is evaporated in the exchange of the heat for moisture.

In my invention any suitable gaseous agent is employed as the drying medium, such as heated air, direct furnace heat, boiler room gases, etc.

The object of my invention is to condition the drying medium as it circulates through

the apparatus so as to keep it in a state of maximum efficiency so far as concerns its capacity for carrying moisture from the material under treatment, such result being obtainable notwithstanding said drying medium carries a relatively high percentage of moisture.

According to this invention, the drying medium is conditioned while circulating through a tunnel drier by conducting it into contact with "boosters" or heaters positioned intermediate the ends of a drying tunnel or chamber, said drying medium flowing into contact first with the material or substance, then with the boosters, and again with the material, and so on throughout the operations, said boosters operating to restore to the drying medium that percentage of heat which is lost by contact with the material and the evaporation of moisture therefrom, whereby the drying medium is reheated or boosted intermediate its periods of contact with the material and said drying medium is thus maintained in a state of maximum efficiency.

It may be stated that owing to the re-heating or boosting the drying medium receives during its circulation through the apparatus, said medium flows out of the latter at the same temperature, or about the same temperature, at which said medium entered said apparatus, plus the moisture evaporated from the material.

For carrying the mass of material into and out of the tunnel, and for supporting said material for treatment therein, I employ wheeled cars or trucks, each of which is novel in construction for the reason that provision is made for the circulation of the drying medium within said truck and into contact, either directly or indirectly, with the material loaded therein.

The boosters or heaters are, or may be, positioned in the top wall of the tunnel, or in the bottom thereof, or in both the top wall and the bottom wall. In positioning the wheeled cars in operative relation to the boosters, the flues of said cars are in register with certain chambers containing the boosters, whereby provision is made for the drying medium to circulate around the boosters and into contact with the loads of the cars.

It may be stated that the path of the drying medium through the wheeled cars may be horizontal, vertical or in other di-

rections, the essential feature consisting in the circulation of the drying medium into contact alternately with the material and with the boosters, whereby the contact of the drying medium with the boosters operates to restore to said drying medium the heat units which become latent due to evaporation; in other words, the boosters restore heat to the drying medium in the intervals between its contacts (either directly or indirectly) with the moisture containing material so as to maintain said medium at a uniform temperature, or substantially so, or even to increase the temperature of said medium, as a result of which reheating operations the drying medium is conditioned for maximum efficiency with respect to its capacity for evaporating moisture from the materials.

20 Other features and advantages of the invention will appear from the following description taken in connection with the accompanying drawings, wherein—

Figure 1 is a vertical sectional elevation 25 through a tunnel drier constructed in accordance with this invention, and illustrating a number of movable carriers or cars positioned within the tunnel and in co-operative relation to the boosters or heaters, 30 the plane of the section being indicated by the dotted line 1—1 of Fig. 2.

Fig. 2 is a horizontal section taken in the plane of the dotted line 2—2 of Fig. 1, showing a plurality of tunnels with the 35 complementary carriers or cars adapted to travel within said tunnels and to be positioned in operative relation to the boosters or heaters.

Fig. 3 is a vertical sectional elevation 40 through another embodiment of the invention wherein the drying medium is adapted to circulate in vertical paths through the wheeled cars or carriers, and the boosters or heaters are positioned at both the top 45 and the bottom of the tunnel.

The drying apparatus shown in Figs. 1 and 2 of the drawings embodies one or a plurality of tunnels, or as they may be termed drying chambers, within which 50 wheeled carriers or cars are adapted to travel for the purpose of conveying the material or substance into and out of the tunnel or drying chamber. It is apparent that the apparatus may embody a single 55 tunnel A, or a plurality of tunnels A, A', A'', but the number of tunnels and the form and dimensions thereof are not material to my invention, hence I reserve the right to 60 employ a single tunnel or any desired number of tunnels, and to give to said tunnels the desired form and dimensions in both longitudinal and cross section.

Each tunnel is equipped with rails forming a track B in the bottom portion thereof, 65 upon which track is adapted to travel the

wheels c of the carriers, trucks, or cars C. It is preferred to employ wheeled carriers, trucks, or cars, the cross sectional dimensions of which are such as to substantially fill the cross sectional dimensions of the 70 tunnel or drying chamber. Each wheeled carrier or car consists of a skeleton frame c' covered by an imperforate casing C' composed of sheet metal or its equivalent. It is preferred to sheath each truck or car with 75 imperforate metal at the two ends and along one side of said truck or car, but it is obvious that the imperforate sheathing C' may extend around the two sides and the two ends of said wheeled car. It is apparent that the skeleton frame c' may be 80 composed of angle iron or other material suitable for the purpose, to which frame the imperforate sheathing C' is adapted to be fastened by rivets, bolts, or other preferred means.

Each wheeled car is equipped with vertical stanchions d positioned parallel to the closed end portions of the car, said stanchions being at a suitable distance from said closed 90 ends so as to result in flues E, E' at the respective ends of each car. The vertical stanchions d support horizontal rails d' upon which rest the horizontal trays D or their equivalents. Said trays serve as the means 95 for supporting the material or substance under treatment, the mass of said material being divided and being disposed in horizontal layers upon the trays. By reference to Fig. 1 it will be noted that the trays D are 100 supported in spaced relation one below the other by the skeleton framework within the car, said trays D being positioned intermediate the flues E, E' at the respective ends of said car. By spacing the trays from each 105 other certain horizontal flues are provided intermediate said trays, said horizontal flues being in communication with the vertical flues E, E', and thus the drying medium admitted to one vertical flue is divided into 110 streams which flow over and beneath the trays and into contact with the masses of material thereon, the drying medium flowing from the spaces over and beneath the trays into the other vertical flue. In this 115 form of the apparatus the drying medium circulates in horizontal paths within the load carrier and it flows into direct and indirect contact with the material on the trays, the vertical flues providing means whereby the 120 drying medium is conducted into and out of the load carrier.

One wall of the tunnel or drying chamber, preferably the top wall thereof, is formed or constructed to produce a plurality of 125 booster containing chambers F, the same being positioned intermediate the entrance to and the exit from said tunnel or chamber. In Fig. 1 the apparatus is shown as having two booster chambers F, but the number of 130

such chambers will depend upon the capacity of the apparatus. As shown, each booster chamber is an integral part of the tunnel structure, but the details of construction 5 may be modified as desired by a skilled constructor.

Within the booster chambers are positioned a plurality of boosters or heaters G, the same being shown as pipes connected 10 with suitable headers whereby a heating medium is adapted to flow into and out of the boosters. It is apparent that any well known heating medium may be employed for circulation through the boosters; obviously, steam is the preferred heating medium, although hot air, furnace gases, boiler room gases, or even electrical energy may be utilized.

Coöoperating with each booster is a deflector H, the same consisting of a horizontal plate positioned intermediate the ends of the booster and preferably at about the middle thereof, and from this horizontal plate a web h extends upwardly toward the 25 booster. The deflector or baffle is adapted to partially divide the booster into compartments so that the drying medium flowing out of one load carrier will be directed upwardly and into contact with the coils of the booster and thence the drying medium 30 will be directed downwardly into the next load carrier, whereby the drying medium flowing out of one load carrier is reheated by the booster to a desired temperature before it flows into the next load carrier, as 35 a result of which the drying medium may be kept at a uniform temperature, or its temperature may be increased as found desirable in the operation of treating the material under consideration.

I designates a flue connected to one end of the tunnel, and I' is another flue connected to the opposite end of said tunnel, whereby a drying medium is adapted to be admitted by the flue I to one end of the tunnel and to make its exit through the flue I' from the opposite end of the tunnel, but intermediate the entrance and the exit of the drying medium it circulates through 50 the closed load carriers and into contact with the boosters alternately, so that the heat lost from the drying medium by contact with said material, and by the evaporation of moisture, will be restored to said 55 drying medium by the contact of the latter with the boosters.

It is apparent that the details of construction may be supplied and altered as desired by a skilled constructor, but in Fig. 1 the 60 entrance to and the exit from the tunnel are adapted to be closed by suitable doors J during the operation of drying the material within said tunnel.

It will be noted that each load carrier is 65 closed at its respective ends and upon one

side by the continuous sheathing C', but the other side of the load carrier should be open to allow for ready access to the trays D, whereby said trays may be introduced and withdrawn as required through said open 70 side of the load carrier. The cross sectional dimensions of the load carrier should conform substantially to the cross sectional dimensions of the tunnel, as shown in Fig. 2, so that a minimum amount of the drying 75 medium will escape from the load carriers through said open sides.

After the load carriers are loaded with the material to be treated, the door at one end is opened and the load carriers are moved 80 successively into the tunnel in a manner well understood by those skilled in the art, the adjacent load carriers being in abutting engagement at their closed ends. The load carriers are positioned within the tunnel for 85 the sheathing C' on the adjacent carriers to register with the baffle H, such relation of the load carriers to the baffle bringing the end flues on adjacent cars into register with the proper booster or heater. The doors to 90 the tunnel having been closed and the heating medium supplied to the boosters, the apparatus is ready for service, whereupon a drying medium, heated to a temperature, suitable for the treatment of the particular 95 material loaded upon the load carriers, is admitted by the flue I. The drying medium flows downwardly into the flue E of one load carrier, thence horizontally over the trays thereof, and thence upwardly through 100 the flue E' of said load carrier. The drying medium comes into contact with the first booster and over the baffle H, so that additional heat units are imparted to it by its contact with said booster, thence said medium is reversed and flows downwardly into 105 the flue E of the second load carrier, thence through the flue E' of said load carrier in an upward direction into contact with the second booster, and so on throughout the 110 series of load carriers and boosters, the drying medium making its exit through the flue I'. When the material of the load carriers is sufficiently dried, the circulation of 115 the drying medium is cut off and the doors 120 are opened, whereupon the cars are shoved out of the tunnel and other cars are introduced into the tunnel, so that the operation of drying material may be carried on almost continuously.

It is apparent that any desired number of tunnels equipped with boosters as desired and adapted for coöperation with a series of load carriers may be employed substantially as indicated in Fig. 2, wherein a series of 125 three tunnels is shown.

Another embodiment of the invention is illustrated in Fig. 3, wherein the masses of material are contained within vertical chambers, and these chambers are arranged to 130

provide vertical flues through which the drying medium is adapted to circulate in vertical paths and so as to have indirect contact with the material under treatment. The 5 tunnel K is provided with an inlet flue k and an exit flue k'. At the bottom of said tunnel is a succession of booster chambers L, and in a similar manner the top of the tunnel is formed with other booster chambers L'. The 10 bottom chambers contain heaters or boosters M, whereas the top chambers contain other heaters or boosters M'. Each series of chambers is divided by imperforate partitions m, and, as shown, said chambers 15 are equipped with baffles M². The load carriers O are provided with vertically positioned chambers P adapted to contain the material to be treated. As shown, the chambers are spaced to produce vertical flues 20 Q within the load carrier, and this load carrier contains a skeleton frame partially or wholly enveloped by an imperforate continuous sheathing C³ so as to produce a car with closed ends.

25 The cars are run into the tunnel for the closed ends thereof to register with the baffles M² and to bring the vertical flues of the car into register with the chambers containing the boosters, the sheathing C³ of said 30 cars extending substantially to the level of the track upon which the cars are run so as to minimize the escape and loss of the drying medium. It is apparent that the drying medium admitted by the flue k circulates 35 downwardly through the flues Q of the first car, thence it flows into contact with the first booster and below the baffle M², thence it flows in an upward direction and through the flues of the second car, thence it flows 40 into contact with the coils of the first upwardly positioned booster and over the baffle M² therein, and thence downwardly through the flues of the third car and so on throughout the series. The drying medium 45 flows into contact with the walls of the vertical chambers P so as to have indirect contact with the material contained therein, but it is reheated by contact with the succession of boosters for the purpose of maintaining it at the desired temperature, or at an increased temperature, as may be found expedient or necessary in the treatment of the 50 particular material loaded in the cars.

Having thus fully described the invention, 55 what I claim as new and desire to secure by Letters Patent is:

1. A drier embodying a chamber or tunnel, a plurality of heaters or boosters positioned intermediate the entrance to and the 60 exit from said chamber or tunnel, and load carriers movable within said chamber or tunnel, each load carrier being closed at the respective ends thereof and said load carriers being provided interiorly thereof with 65 flues adapted to register with said heaters

or boosters whereby a drying medium is adapted for circulation through the flues of said load carriers and into contact with said heaters or boosters.

2. A drying apparatus embodying a 70 chamber or tunnel provided with an inlet and an outlet for a drying medium, a plurality of load carriers movable within the tunnel or chamber, each load-carrier being provided with material supporting means and 75 with flues through which is adapted to circulate the drying medium, means for circulating a drying medium back and forth through said chamber or tunnel and through the flues of said load carrier, said back and 80 forth circulation of the drying medium being intermediate the inlet and the exit of said tunnel or chamber, and boosters or heaters positioned in the walls of the chamber or tunnel, intermediate said inlet and exit, and 85 exposed for contact with the drying medium in the course of the back and forth circulation thereof, said boosters or heaters operating to reheat the drying medium in the intervals between its contacts with the material under treatment, whereby the drying medium is kept in an efficient condition for giving up its heat in exchange for moisture.

3. A drying apparatus embodying a 90 chamber or tunnel provided with an inlet 95 and an exit for a drying medium, a plurality of load carriers movable within said chamber or tunnel, each load carrier having means for supporting the material under treatment, booster chambers in the walls of the tunnel or chamber and in communication therewith, means for circulating a drying medium back and forth through the tunnel or chamber and through the booster chambers and into contact with the material upon 100 the load carriers, and boosters or heaters positioned within the booster chambers and operating to reheat the drying medium in the intervals between its contacts with said material under treatment, said load-carriers 110 being provided with flues adapted to communicate with the booster chambers so that the reheated drying medium flowing out of said booster chambers is conducted into contact with the material upon said load carriers.

4. A drying apparatus embodying a 115 chamber or tunnel provided with an inlet and an exit for a drying medium, a plurality of load carriers movable within said chamber or tunnel, each load-carrier having means for supporting the material under treatment, booster chambers in the walls of the tunnel or chamber and in communication therewith, means for circulating a drying 120 medium back and forth through the booster chambers and into contact with the material upon the load-carriers, and boosters or heaters positioned within the booster chambers and operating to reheat the drying medium 125 130

in the intervals between its contacts with said material under treatment, each load-carrier being closed at the ends thereof and said load-carriers being provided intermediate said closed ends with flues adapted to register with the booster chambers so that the reheated drying medium flowing out of the booster chambers is adapted to circulate within the load carriers and into contact with the material thereon.

5. A drying apparatus embodying a chamber or tunnel, load-carriers movable therein, means for circulating a drying medium within the chamber and the load carriers, and boosters positioned in the walls of the chamber at points intermediate the entrance to and the exit from the chamber, each load-carrier being sheathed for closing the ends and at least one side thereof, and 10 said load-carrier being provided within the same with means for supporting the material under treatment and with flues for the

circulation of the drying medium, said load-carriers being so related to the boosters that the drying medium circulates into contact 25 alternately with the material under treatment and with said boosters.

6. A drying apparatus embodying a chamber, load-carriers movable therein, means for circulating a drying medium 30 within said chamber, and boosters positioned within compartments provided in the walls of said chamber, each load-carrier being sheathed for closing the ends and at least one side thereof, and said load-carrier being 35 provided with horizontal material-supporting means arranged relatively to the closed ends to produce vertical flues, which latter flues are in communication with horizontal flues produced by spacing apart the said 40 horizontal material-supporting means.

In testimony whereof I have hereunto subscribed my name.

GORDON DON HARRIS
